UNITED STATES PATENT OFFICE.

WILHELM MAIER, OF VILLINGEN, GERMANY.

DESIGN FOR A CLOCK CASE.

Application filed January 4, 1922. Serial No. 4,808. Term of patent 14 years.

To all whom it may concern:

Be it known that I, WILHELM MAIER, a citizen of the German Republic, and a resident of Villingen, Badenia, Germany, have invented a new, original, and ornamental Design for Clock Case, of which the following is a specification, reference being had to the accompanying drawing, forming part thereof.

The figure is a perspective view of a clock case showing my new design.

I claim:

The ornamental design for a clock case as shown.

WILHELM MAIER.

In the presence of—

ALFRED GEIGER,
MAURICE W. ALTAFFER.
